UNITED STATES PATENT OFFICE.

LEOPOLD KEHLMANN, OF NEW YORK, N. Y.

CIGARETTE-MAKING MACHINE.

1,274,168.

Specification of Letters Patent. Patented July 30, 1918.

Application filed March 19, 1918. Serial No. 223,282.

To all whom it may concern:

Be it known that I, LEOPOLD KEHLMANN, a citizen of the United States, and resident of New York city, borough of Manhattan, 5 in the county of New York and State of New York, have invented certain new and useful Improvements in Cigarette-Making Machines, of which the following is a specification.

10 The object of my invention is to provide a simple and efficient machine or device for manually making cigarettes, and has particular reference to a relatively small and compact machine to enable a smoker to 15 make the cigarettes for his personal use.

My invention comprises novel details of improvement and combinations of parts that will be more fully hereinafter set forth and then pointed out in the claims.

20 Reference is to be had to the accompanying drawings forming part hereof, wherein, Figure 1 is a plan view of a cigarette making machine embodying my invention, with its cover thrown back, and the parts 25 in position for receiving the tobacco; Fig. 2 is a section on the line 2, 2, in Fig. 1; Fig. 3 is a side view of the machine with its cover closed; Fig. 4 is a plan view of Fig. 3; Fig. 5 is a section on the line 5, 5, 30 in Fig. 4, illustrating the position of the cigarette paper and cigarette rolling members before completion of the cigarette; Fig. 6 is a similar view illustrating a rolled cigarette in the machine, and Fig. 7 is a 35 fragmentary detail of a tobacco pusher.

Similar numerals of reference indicate corresponding parts in the several views.

The numeral 1 indicates a suitable framing or casing, which may be of any desired 40 construction, either closed at the sides and bottom, or open for the escape of tobacco, and at 2 is a cover or movable member suitably hinged to frame 1 and provided with a transverse slot 3 for the passage into the 45 machine of the cigarette papers 4. The cover 2 is shown pivotally carried by frame 1 by a pin 5 extending through the frame on which the ears 6 of cover 2 are hung. At 50 7 is a roller journaled in frame 1, as by means of its pivots 7^a, and 8 is a corresponding roller rotatively and slidably supported in the frame opposing roller 7. The pivots 8^a of roller 8 are respectively mounted in slots 9 in the opposing side portions of 55 frame 1, whereby the roller 8 may move toward and from roller 7. At 10 is an endless

belt or apron of any suitable flexible material, inclosing rollers 7 and 8, and made sufficiently loose with respect to said rollers to permit the opposing webs of said belt 60 to be depressed in the nature of a bight at 11 to receive the tobacco 12 for the cigarette charge. While the tobacco may be arranged in the bight of the belt by the fingers of the user, a convenient means for 65 pressing the tobacco in the belt may be a bar 13 having a longitudinal groove 13^a in one edge, which bar may be pressed upon the tobacco between the rollers 7, 8, as indicated in Fig. 2. At 14 is an operating roller 70 rotatively and slidably mounted in the slot 9. Said roller 14 is shown provided with a reduced portion at 15 to slidably receive one of the side members of frame 1 to keep the roller from longitudinal movement. Roller 75 14 may be provided with a covering 16, such as of rubber or leather, of a tenacious nature for coöperation with belt 10. When the roller 14 is held pressed operatively in connection with roller 8, and is rotated, the 80 latter, together with the belt, and thereby the roller 7, will all be operated to roll the tobacco 12 in the belt. As a convenient means for retaining the roller 14 pressed operatively against belt 10 and roller 8, I 85 have shown the cover 2 provided with means to press the roller 14 toward roller 8 when the cover is closed, and to release said roller 14 when the cover is raised. The means I have shown comprises cam-like projections 90 17 secured upon the under side of the cover 17 adjacent to its pivotal point and shown within the frame, whereby when the cover is open, as in Figs. 1 and 2, the roller 8 will be free to move away from roller 7, and 95 when the cover is closed projection 17 will coöperate with roller 14 to push it toward roller 8 and thereby to push roller 8 toward roller 7 to retain the tobacco in the bight of the belt.

I have illustrated means for conveniently moving rollers 8 and 14 in the direction away from roller 7, for the ready admission of the tobacco in the belt when the cover has been raised. For such purpose I have 100 shown arms 25 pivotally supported on opposite sides of frame 1 at 26, which arms are connected by a cross bar 25^a, whereby said arms may be moved together, the arms 25 and bar 25^a, thus being somewhat in the 110 nature of a bail. The arms 25 may rest upon suitable stops, such as upon projecting

5 pivots 7^a of roller 7, whereby said arms will have their operative portions in front of the pivots 8^a of roller 8. The arms 25 are shown extending diagonally from their pivots 26 to a position in front of pivots 8^a, the arrangement being such that when cover 2 is raised the arms 25 may be operated by swinging the bar 25^a and said arms to the left in Fig. 3, whereby said arms will engage the pivots 10 8^a to push roller 8 and thereby roller 14 to the left in the drawings to spread said rollers from roller 7 (Fig. 2). The arms 25 and bar 25^a may be swung back to position shown in Fig. 3 when the tobacco is to be inserted 15 in the belt, and thereafter the cover may be closed.

20 As a means for pushing the cigarette up from the bight of the belt I provide a pusher or extractor beneath the belt indicated at 18, which is shown extending laterally from a rod 19 journaled at 20, 21 upon the frame 1, and provided with a handle or finger piece 22 on the exterior of the frame. By rotating the rod 19 the pusher 18 may be 25 swung up to lift the rolled cigarette with the loose portion of the belt between the rollers 7 and 8 in convenient position for removal by the fingers of the operator.

25 When it is desired to make a cigarette, the cover is opened and the rollers 14 and 8 are moved toward the left in the drawings to permit the insertion of the tobacco 12 in the bight of the belt, and then the cover is closed whereby the rollers 14 and 8 will 30 move to the right substantially as indicated in Figs. 5 and 6. The roller 14 may then be rotated by means of its handle 14^a to firmly roll the tobacco, and then the cigarette paper 4 may be inserted through slot 3 of the cover 35 between the rollers 7 and 8 so as to be engaged between the tobacco and belt 10 as indicated in Fig. 5, and upon continued rotation of roller 14 the latter will cause operation of the belt and rolling of the tobacco 40 within the cigarette paper, substantially as indicated in Fig. 6. Lateral pressure of roller 14 against the belt and roller 8 causes the belt to roll the cigarette to the desired extent, and the material at the end of slots 45 9 will limit the approach of roller 8 to roller 7 so that the cigarette will not be wound too tightly. The cigarette paper may be supplied with gum or the like along one edge at 4^a, and may be moistened before the gummed 50 edge of the paper passes through slot 3 of the cover, so that when the paper is completely wound around the tobacco filler the paper will stick together. The upper surface of the cover affords a base upon which 55 to rest the outer part of the gummed edge of the paper when applying moisture thereto, as for instance, when the paper has been partially wound so as to bring its gummed edge 60 near to the cover. When the cigarette has 65 been rolled the cover may be swung back and

the rollers 14, 8 separated to permit removal of the cigarette from the belt.

Changes may be made in the details of construction and arrangement of parts set forth, since the same may be varied, within 70 the scope of the appended claims, without departing from the spirit of the invention.

75 While I have referred to my improvements as being adapted for the manual making of cigarettes, it will be understood that the same may be utilized in a machine for the manufacture of cigarettes for sale, and also that material other than loose tobacco may be wrapped in accordance with my invention, such as cigars, candies and other 80 articles. Hence, by the term "cigarette rolling machine" as herein used I means to include the rolling of other articles than cigarettes.

Having now described my invention what 85 I claim is:—

1. A cigarette rolling machine comprising a frame, a pair of spaced rollers journaled therein, an endless belt upon said rollers, means for movably guiding one of 90 said rollers for movement toward and from the other, an operating roller laterally movably supported by the frame to move toward and from and for coöperation with the other laterally movable roller for operating the belt, and means to retain said last named rollers in coöperation for operation of the belt.

2. A cigarette rolling machine comprising a frame, a pair of spaced rollers journaled therein, an endless belt upon said rollers, means for movably guiding one of 100 said rollers for movement toward and from each other, an operating roller movably supported by the frame for coöperation with the other laterally movable roller for operating the belt, and one or more projections 105 movably supported and coöperative with the operating roller to retain it in coöperation with said laterally movable roller for operation of the belt.

3. A cigarette rolling machine comprising a frame, a pair of rollers journaled therein and spaced apart, an endless belt on 115 said rollers, said frame having slots supporting one of said rollers for lateral movement, and an operating roller supported in said slots for lateral movement independently of and to coöperate with the last named roller for operation of the belt.

4. A cigarette rolling machine comprising a frame, a pair of rollers journaled therein and spaced apart, an endless belt on 120 said rollers, said frame having slots supporting one of said rollers for lateral movement, an operating roller supported in said slots for lateral movement to coöperate with the last named roller for operation of the belt, and one or more projections 125 movably supported and coöperative with the 130

operating roller to retain it in coöperation with said laterally movable roller.

5. A cigarette rolling machine comprising a frame, a pair of spaced rollers journaled therein, an endless belt upon said rollers, means for movably guiding one of said rollers for movement toward and from the other, an operating roller movably supported by the frame for coöperation with the other laterally movable roller for operating the belt, and a cover upon the frame having a slot for the passage of cigarette papers, said slot being in position when the cover is closed to guide the paper between the first named rollers.

6. A cigarette rolling machine comprising a frame, a pair of spaced rollers journaled therein, an endless belt upon said rollers, means for movably guiding one of said rollers for movement toward and from the other, an operating roller movably supported by the frame for coöperation with the other laterally movable roller for operating the belt, a cover for the frame provided with one or more projections cooperative with the operating roller for retaining the latter in operative relation to the belt and for operation of the latter.

7. A cigarette rolling machine comprising a frame, a pair of spaced rollers journaled therein, an endless belt upon said rollers, means for movably guiding one of said rollers for movement toward and from the other, an operating roller movably supported by the frame for coöperation with the other laterally movable roller for op-

erating the belt, and a pusher movably carried by the frame opposing the belt to move the cigarette into position for removal from between the first named rollers.

8. A cigarette rolling machine comprising a frame, a pair of spaced rollers journaled therein, an endless belt upon said rollers, means for movably guiding one of said rollers for movement toward and from the other, an operating roller movably supported by the frame for coöperation with the other laterally movable roller for operating the belt, and means movably carried by said frame for coöperation with said movable roller for moving it and the corresponding portion of the belt away from the companion roller.

9. A cigarette rolling machine comprising a frame, a pair of spaced rollers journaled therein, an endless belt upon said rollers, means for movably guiding one of said rollers for movement toward and from the other, an operating roller movably supported by the frame for coöperation with the other laterally movable roller for operating the belt, a pair of arms pivotally carried by said frame in operative relation to the movable roller, and a bar connecting said arms whereby said arms may be swung to move said movable roller and the corresponding portion of the belt away from the companion roller.

Signed at New York city, in the county of New York and State of New York, this 18th day of March, A. D. 1918.

LEOPOLD KEHLMANN.
